CLAIM

The ornamental design for an electrostatic disinfecting sprayer, as shown and described.

DESCRIPTION

FIG. 1 is a front, top left perspective view of a first embodiment of the electrostatic disinfecting sprayer showing my new design.

FIG. 2 is a rear, right, top perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a left side elevation view thereof.

FIG. 8 is a right side elevation view thereof.

FIG. 9 is a front, top left perspective view of a second embodiment of the electrostatic disinfecting sprayer showing my new design.

FIG. 10 is a rear, right, top perspective view thereof.

FIG. 11 is a front elevation view thereof.

FIG. 12 is a rear elevation view thereof.

FIG. 13 is a top plan view thereof.

FIG. 14 is a bottom plan view thereof.

FIG. 15 is a left side elevation view thereof; and,

FIG. 16 is a right side elevation view thereof.

The subject matter depicted in broken lines forms no part of the claimed design.
